UNITED STATES PATENT OFFICE.

EDWARD A. LANGENBACH, OF CANTON, OHIO.

DESIGN FOR MOLDING.

SPECIFICATION forming part of Design No. 24,485, dated July 16, 1895.

Application filed June 10, 1895. Serial No. 552,344. Term of patent 7 years.

To all whom it may concern:

Be it known that I, EDWARD A. LANGENBACH, a citizen of the United States, and a resident of Canton, county of Stark, State of Ohio, have invented and produced a new and useful Design for a Molding for Metallic Walls or Siding, of which the following is a full, clear, and exact description, reference being had to the accompanying drawings, making part of this specification.

My invention relates to a design for a molding for metallic walls or sidings.

In the accompanying drawings, Figure 1 is an elevation of a molding made according to my design. Fig. 2 is a vertical section of the same.

My design consists of a molding having the shape or configuration in cross-section shown in Fig. 2 and ornamented, as hereinafter described.

The letter A designates a curved lower horizontal portion and B the upper portion of the molding. Said lower portion is formed at regular intervals apart with a series of ribs C, comprising vertical portions connected to-

gether at the inner ends by horizontal ribs D, and inclosed within the figure thus formed is a series of ornamental projections E in relief. Between each two said portions C is a tapering portion F in relief, having a curved or rounded upper end. Above said horizontal lower portion are a number of ogee-shaped projections G, curved or rounded at the upper part, and between each of said ogee-shaped portions are approximately diamond-shaped portions H in relief, also formed with rounded heads I. These figures or portions G and H are bounded by ribs or curved projections K. At the top edge the molding is formed with a series of alternating ribs L and circular projections M.

What I claim is—

The design for a molding herein shown and described.

In testimony whereof I have hereunto set my hand this 17th day of May, A. D. 1895.

EDWARD A. LANGENBACH.
